TURN-TABLE MECHANISM FOR RAILWAY PILE-DRIVERS AND THE LIKE.

982,418.

Specification of Letters Patent. Patented Jan. 24, 1911.

Application filed January 26, 1910. Serial No. 540,173.

To all whom it may concern:

Be it known that I, WALTER FERRIS, a citizen of the United States, and resident of South Milwaukee, county of Milwaukee, and 5 State of Wisconsin, have invented certain new and useful Improvements in Turn-Table Mechanism for Railway Pile-Drivers and the Like; and I do hereby declare the following to be a full, clear, and exact description of the invention, such as will enable others skilled in the art to which it appertains to make and use the same.

This invention relates to railway pile drivers, steam shovels, snow plows, or other 15 machines which may need to be reversed to enable them to get at their work.

It has special reference to apparatus of this kind in which the car body on which the machine is mounted carries at its under 20 portion a turn table which may be supported on the railway track and on which the car and machine as a whole may be turned end for end, in order to reverse its direction.

The object of the invention is to provide 25 an improved form of turn table, an improved arrangement of the turn table with respect to the car body, and improved mechanism for raising and lowering the turn table as a whole with respect to the car, so that the 30 latter may be elevated and swung around through 180°, after which the turn table is moved upward from its operative position, wherein it supports the car, to a position directly beneath the bottom or deck of the 35 latter, in which position it will not interfere with the track when the machine is being transported from place to place.

I also aim to provide improved mechanism, operating in connection with the turn 40 table, by means of which the car body may be swung end for end by hand power after it has been lifted from the track, as just indicated.

In carrying out the invention, the turn 45 table is constructed of upper and lower frames that are mounted beneath the bottom of the car and held together against relative vertical and turning movements when the turn table is not in use, each frame 50 being provided with a ball race between which and the ball race of the other frame anti-friction balls are interposed, so that the swinging about of the car may be effected with a minimum of friction. Extending

down from the side beams of the car at the 55 corners of the turn table are suitable pedestals on which are pivoted bell crank levers, said levers being also pivoted to the upper member of the turn table. These levers are preferably arranged in sets at opposite sides 60 of the car and they are operated by means of hydraulic cylinders which, when the lower member of the turn table is supported from the track by means of suitable jacks, effect uniform pivotal movements of said 65 bell crank levers about the pivots carried by the upper turn table member, whereby the car body as a whole is raised by upward pressure applied to the aforesaid pedestals. The lower member or frame of the turn 70 table is provided with an internal gear and when the car body has been raised as indicated, the swinging about of the same is produced by a manually operated geared connection with said internal gear. When the 75 car body is raised, the two members of the turn table must be freed from each other in order to allow the turning of the upper member on the lower one, as will be understood, but when the swinging around of the car 80 body is completed, and after it has been lowered again onto the rails, the two turn table members are again locked together, the jacks removed, and the turn table as a whole raised into shipping position by a movement 85 of the bell cranks in a direction opposite to that first indicated.

In the accompanying drawing:—Figure 1 is a side elevation of a railway pile driver provided with turn table mechanism constructed in accordance with the invention, Fig. 2 is an enlarged side elevation of the turn table mechanism, with certain parts removed and other parts shown in section, the apparatus being shown in the position 90 it occupies when the pile driver is on the track, Fig. 3 is a view similar to Fig. 2, but showing the car body raised, Fig. 4 is a top plan view of the turn table mechanism, one half showing the upper frame or member, 100 and the other half showing the lower frame or member, and Fig. 5 is a transverse section through the car body and the turn table mechanism.

In the accompanying drawing, 10 indicates the car body, on which is mounted mechanism of any preferred type, the particular form of this mechanism being entirely

inmaterial to the invention. In the embodiment shown, which is a pile driver, the car carries a leader frame 11 which is adapted to be erected at one end of the machine, as indicated in dotted lines, and it is obvious that by the swinging of the pile driver through 180° the leader frame can be swung around to operate at opposite points. The car body is adapted to travel on the track rails 12 by means of wheels 13 and the pile driver may be of the self propelled type or not, as desired.

Underneath the body 10, at a point intermediate of the ends of the pile driver, there is mounted a turn table composed of an upper frame 14 and a lower frame 15, which frames are adapted to have a relative turning movement when the lower frame is supported on the track by means of chairs 16 and the car body is raised from the track, said body together with the upper frame 14 then being swung around on the lower frame 15 which serves as a foundation for the entire pile driver during this swinging movement. The raising of the car body is effected by means of levers 17—18 arranged in pairs at opposite sides of the car body and supported thereon, said levers being operated by means of hydraulic or other cylinders 19 carried at the sides of the car.

Referring especially to Figs. 2 and 4, it will be observed that the upper frame 14 of the turn table is approximately square in shape, said frame embodying front and rear structural channel bars 14^a connected by a steel casting 14^b, the lower part of which is formed into a circular flange 20, preferably of I-cross section. The lower frame or member is likewise made approximately square and it comprises side members 21 formed of suitable channels and connected by a steel casting 22, the upper part of which is formed into a circular flange 23 corresponding to the flange 20 and arranged immediately beneath the latter. The base of the flange 20 and the head of the flange 23 are machined to receive anti-friction balls 24 that are interposed between them, and said flanges therefore constitute ball races 25 that are carried by the respective turn table frames. Dust is prevented from reaching the balls 24 by means of suitable dust rings 26. The two frames are locked together by means of suitable clamps 27 that are located at different points in the circle of the ball races and serve to support the lower ball race and frame from the upper frame when the entire turn table is raised into the shipping position.

The upper frame 14 carries at its corners laterally projecting pins 27, and each of these pins is made sufficiently strong to bear one quarter of the weight of the entire pile driver. Pivoted on these pins are the operating levers 17 and 18 previously referred to,

said levers being mounted to move in a vertical plane at the side of the car body, and being also pivoted, by means of pins 28, to the lower ends of brackets or pedestals 29 that are bolted to the under surface of each side beam 10^a of the car body by means of flanges 30 cast on the upper ends of said pedestals. The levers 17—18 are of the bell crank-type, and it will be noted that the pivots 28, which are alined with the upper arms of the levers, form fulcrums about which the pins 27 may be moved downward in order to depress the turn table supported thereby. The upper arm of each lever 17 is directly connected to a connecting rod 31 of trunk piston 32 that operates in the hydraulic cylinder 19, which cylinder is preferably bolted onto the side beam 10^a. The upper arm of the bell crank lever 17 is connected with the upper arm of the bell crank lever 18 by means of a connecting rod 33, so that the force transmitted to said lever 17 by the hydraulic cylinder and piston will be transmitted to the lever 18, as will be obvious. The connecting rod 33 extends in parallelism to the side beam 10^a and alongside a bracket 34 to which it may be locked by a pin 35, for a purpose which will presently appear. Both the connecting rod 31 and the connecting rod 33 are preferably built up of separate bars, one of which is angular in cross section, as appears from Fig. 5. It will, of course, be understood that the same construction is used at both sides of the car, as appears from Figs. 4 and 5, and in order to transmit a greater lifting effort to one side of the car when the center of gravity of the car is not over the center line of the track, the levers 17 are provided with rearwardly-extending arms 37 that are connected by a cross shaft 38 extending transversely beneath the car body. In this way, the levers 17 are caused to act in unison when pressure is transmitted to them from the hydraulic pistons, although the resistances on the two sides of the machine may be unequal.

At the corners of the lower turn table frame 15, the latter is provided with jack screws 39 which are actuated by means of hand wheels 40 (Fig. 5), and when said screws are lowered they may be caused to engage at their lower ends with the track chairs 16 previously mentioned. One of these chairs is placed on the track at each corner of the lower turn table frame and the pairs of chairs are connected by transverse channels 41. When the chairs are not in use they may be supported in slipping position on the lower frame 15 by means of bars 42 applied to the sides of said frame near the corners and extending forward and rearward of the turn table, the chairs being suspended on said bars by means of detachable pins 43, as indicated in Fig. 2.

The hydraulic cylinders 19 are connected by

means of pipes 44 and 45 to a four-way valve 46, which in turn is connected to a pump 47 illustrated diagrammatically in Figs. 2 and 3. Said pump, in practice, is placed at any suitable point on the car body and it is preferably driven by means of steam from the boiler of the pile driver. The pipe 44 communicates with the interior of the cylinder through an opening in the cylinder head 48, while the pipe 45 is connected with the cylindrical wall of the cylinder near the opposite end, so that water introduced through the pipe 45 acts on the rear surface of the piston head 32^a while water introduced through the pipe 45 enters the annular space between the cylinder wall and the annular shell 32^b of the trunk piston. The four-way valve 46 may be operated in any convenient way, as by the crank 49, and the valve is so constructed and arranged as to permit the exhaust water passing out of the pipe 45 or 44, as the case may be, to escape through an exhaust pipe 50 connected with the valve casing, it being evident that when the pipe 44 is exhausting, water will be supplied from the pump through the pipe 45, and vice versa. It is to be understood, however, that this particular manner of controlling the operation of the cylinder and piston does not affect the gist of the invention.

The mechanism just described serves to raise the car body when it is supported on the chairs of the lower turn table frame, and I will now proceed to describe the devices by which the car body may be swung end for end by hand power after it has been raised up from the rails. This mechanism comprises an internal gear 51 suitably secured to the upper part of the lower ball race 23, and meshing with said gear is a pinion 52 carried by the lower end of an upright stud shaft 53 journaled in fixed brackets or bearings 54 that are applied to transverse bars 55 carried by the upper ball race 45 casting 14^b. At the intermediate portion of the stud shaft 53, the same carries a worm wheel 56 that engages a worm 57 carried by a transverse operating shaft 58 that has bearings at its ends in the upper ball race 50 casting 14^b. In Fig. 4, one of these bearings is indicated at 59, and it is to be noted that the bearing at the opposite side is similarly formed. The shaft 58 also has intermediate bearings 60 supported by the transverse bars 5 or plates 55, and it is between these bearings 60 that the worm is located, so that the latter is rigidly held in its proper relation with the worm wheel 56. Applied to the opposite ends of the operating shaft 59 are removable hand cranks 61. It is to be understood that although the internal gear is carried by the lower ball race, the rest of the swinging mechanism comprising the pinion, worm gear, and worm shaft, is all carried by the frame of the upper ball race,

so that when the cranks 61 are rotated, the pinion 52 will be rotated and moved along the inner circumference of the internal gear, which, of course, is fixed against rotation, the result being that the upper turn table 70 frame and the car body will be swung around until the pile driver is placed end for end.

The operation of the apparatus may be briefly described as follows: When it is desired to swing the pile driver end for end, the chair frames 16, 41 will be removed from their shipping position on the brackets or bars 42 of the lower turn table frame and placed on the rails beneath the jacks 42 at the corners of said frame, the jack screws being so adjusted that their lower ends are near the tops of the chairs 16. At this time, the turn table will be in its uppermost position, each trunk piston 32 being located 85 adjacent the cylinder head 48 and the levers 17-18 having the position indicated in Fig. 2. Pressure water will then be pumped from the pump 47 through the cylinder heads 48 by way of the pipes 44, the four-way valve 46 being suitably manipulated to produce this result, and it is obvious that the pressure of the water in each cylinder 19 will cause the piston rod 31 to be thrust outward, as indicated in Fig. 3. This movement of the piston rod will cause the upper end of the corresponding bell crank 17 to move a short distance about the corresponding pin 28 as a pivot, until the pin 27 carries the turn table down onto the chairs with 100 the jacks resting on the latter, whereupon the lever is moved about the pin 27 as a pivot because said pin is maintained against further depression by reason of the fact that the turn table is held up by the chairs and 105 jacks. Accordingly, the pin 28, that is carried by the pedestal 29, will be forced upward, as shown in Fig. 3, carrying with it the pedestal and the entire car body, to which latter the pedestal is bolted. The car 110 body will therefore be raised to such an extent that its wheels will clear the rails, the center bearings of the car trucks being suitably constructed to effect this result. The movement of each lever 17 is transmitted to 115 the corresponding lever 18 by means of the connecting rod 33, as before explained, and all four of the levers will therefore operate in the same way. If the center of gravity is at one side of the car center line, the cross 120 shaft 38 connecting the two levers 17, will transmit from the lifting cylinder on the light side to the pair of levers on the heavy side sufficient lifting force to bring the center of lifting effort under the center of 125 gravity whereby the same raising effect will be produced at all four corners of the turn table.

When the parts have reached the position shown in Fig. 3, the car body can be 130

swung end for end by means of the manually operated worm shaft 58, as before indicated, the upper ball race rolling freely on the balls 24. When the car has been swung 5 through 180°, it can be lowered again, and this can be effected by so manipulating the four-way valve 46 that the pressure water acting on the piston head will be exhausted, whereby the car is permitted to settle down 10 onto the rails, the levers being moved back toward their initial position. This manipulation of the four-way valve also causes pressure water to be admitted to the cylinder through the pipe 45, which water will fill 15 the space between the shell of the piston and the cylinder wall and act against the front face of the piston over a relatively narrow annular surface, whereby the levers 17 and 18 will be brought all the way back to 20 their initial position in order to restore the car body and turn table to their original relative positions. Before the pile driver is moved again, the chair frames 16, 41 are hung on their brackets 42, so that there will 25 be no interference with the track, and each connecting rod 33 is locked in position by means of the before mentioned pin 35 which secures the connecting rod to the bracket 34 in the manner indicated in Fig. 4, where- 30 by the movement of the bell crank levers and the settling of the turn table, during the transportation of the pile driver, are effectively prevented. It will be noted that the lower frame or member 15 of the turn 35 table is substantially below the side beams of the car in all of its positions, and accordingly it does not interfere with the car body or any parts carried thereby when the pile driver is swung around.

40 It will be understood that the mechanism illustrated and described is only one embodiment of my inventive idea, and that I have not attempted to describe the modifications that may be adopted without departing 45 from the invention.

What I claim is:—

1. The combination of a car body, a portable turn-table carried thereby and vertically movable in relation thereto, a system of interconnected levers to raise the car body with respect to the turn table when the latter is supported on the rails, and fluid pressure devices acting directly on certain of said levers.
- 55 2. The combination of a car body, a turn table carried thereby, and means to raise the car body with respect to the turn table when the latter is supported on the track rails, said means comprising fluid pressure devices carried by the car body.
- 60 3. The combination of a car body, a turn table at the under portion thereof and movable vertically with respect to said body, a system of levers to raise the body with

respect to the turn table, and fluid pressure mechanism to operate the levers.

4. The combination of a car body, a turn table carried thereby and movable vertically with respect thereto, levers arranged in pairs at opposite sides of the car body and operative to raise and lower the latter with respect to the turn table, and a fluid pressure device to actuate each pair of levers.

5. The combination of a car body, a turn table movable vertically with respect to the same, bell crank levers connected to the turn table and to the car and operative to raise the latter with respect to the turn table, said levers being arranged in pairs at the sides of the car body, and a fluid pressure cylinder and piston to operate each pair of levers.

6. The combination of a car body, a vertically movable turn table carried thereby, levers connected to the turn table and to the car body and operative to raise the latter with respect to the turn table, a cross shaft connecting said levers, and power operated means to operate said levers.

7. The combination of a car body, a vertically movable turn table carried thereby, levers arranged at opposite sides of the car and pivoted to the latter and to the table, hydraulic cylinders supported on the car, and pistons in said cylinders operatively connected with the levers.

8. The combination of a car body, a turn table movable vertically with respect thereto and comprising upper and lower frames or members, pins projecting laterally from the upper frame of the turn table, pins carried by the car body beneath the side beams of the latter, and a system of power operated levers each of which is pivoted on a pin on the turn table frame and a pin on the car body.

9. The combination of a railway car, a system of lifting levers carried by the car, a turn table carried by the lifting levers, hydraulic cylinders actuating the lifting levers, and a pump to pump water into the cylinders.

10. The combination of a railway car, a turn table carried thereby, a lifting mechanism comprising a pair of bell cranks at each side of the car, a connecting rod to maintain the bell cranks of each pair in parallel relation, means extending across the car to maintain the opposite pairs of bell cranks in the same angular position, and power mechanism acting on the bell crank system.

11. In a railway pile driver or the like, a car, a vertically movable turn table at the under portion thereof and comprising upper and lower frames, pins extending laterally from the upper frame, jacks carried by the lower frame, levers pivoted on said pins and connected to the car body to raise the

same, and power operated mechanism acting on the levers.

12. In a railway pile driver or the like, a car, a vertically movable turn table carried thereby and comprising upper and lower approximately square frames, having a rotative relation to each other, jacks at the corners of the lower frame, levers pivoted to the corners of the upper frame and operatively connected to the car body to raise the same with respect to the turn table, and means to operate all of the levers simultaneously.

13. In a railway pile driver or the like, a car, a portable turn table carried thereby and vertically movable with respect to the same, said turn table comprising upper and lower ball races, an internal gear carried by the lower ball race, a pinion carried by the upper ball race and meshing with said gear, and a transverse shaft to operate said pinion.

14. In a railway pile driver or the like, a car, a turn table movable vertically with respect thereto and comprising upper and lower frames equipped with cooperating ball-races, an internal gear carried by the lower frame, means to hold the lower frame stationary on the rails, a pinion carried by the upper frame and meshing with said gear, and means to rotate said pinion and thereby swing the upper frame with respect to the lower frame.

15. In a railway pile driver or the like, a car, a portable turn table carried thereby and vertically movable with respect to said car, means to raise the car on the turn table as a foundation, and means to swing the car in a horizontal plane, comprising gear mechanism associated with the turn table, and a transverse operating shaft.

16. In a railway pile driver or the like, a car, a portable turn table carried thereby and vertically movable with respect to said car, means to raise the car on the turn table as a foundation, and means to swing the car in a horizontal plane, comprising gear mechanism associated with the turn table, a transverse operating shaft, and hand cranks applied to the ends of said shaft and located at opposite sides of the car.

17. In a railway pile driver or the like, a car, a portable turn table carried thereby and vertically movable with respect to the car, said turn table comprising upper and lower frames or members, and means to swing the car in a horizontal plane, including gear mechanism associated with the turn

table, and a transverse horizontal operating shaft having bearings at its end portions in the upper turn table frame.

60

18. In a railway pile driver or the like, a car body, a vertically movable turn table carried thereby, mechanism to depress the turn table into engagement with fixed supporting devices on the track and to then raise the car body on the turn table as a foundation, fluid pressure cylinders and pistons in said cylinders having opposite active surfaces of different area and operatively connected with the aforesaid mechanism, the larger piston area being used to elevate the car body and the smaller area effecting the return of the turn table into its elevated or shipping position.

19. In a railway pile driver or the like, a car body, a vertically movable turn table carried thereby, mechanism to depress the turn table and raise the car body with respect to the latter, and hydraulic cylinders supported on the car and having trunk pistons operating therein and connected with said mechanism, the larger active area of each piston producing the raising of the car body and the smaller active area effecting the return of the turn table into its elevated position.

20. The combination of a car body, a turn table carried thereby and vertically movable with respect thereto, lifting levers at the sides of the car pivoted to the turn table and to the car body, means connecting the levers at the same side of the car, means to connect the levers across the car, and power operated devices at opposite sides of the car, operatively connected with the connected system of levers.

21. The combination of a car body, a turn table carried thereby and vertically movable with respect thereto, lifting levers at the sides of the car pivoted to the turn table and to the car body, means connecting the levers at the same side of the car, means to connect the levers across the car, and power operated devices at opposite sides of the car, comprising fluid pressure cylinders fixed to the car, and pistons in said cylinders connected with certain of said levers.

In testimony whereof I affix my signature, in presence of two witnesses.

WALTER FERRIS.
